(57) **CLAIM**

The ornamental design for a mobile computer, as shown and described.

DESCRIPTION

FIG. 1 is a front perspective view of an embodiment of a mobile computer;

FIG. 2 is a rear perspective view of the mobile computer of FIG. 1;

FIG. 3 is a top elevational view of the mobile computer of FIG. 1;

FIG. 4 is a bottom side view of the mobile computer of FIG. 1;

FIG. 5 is a top side view of the mobile computer of FIG. 1;

FIG. 6 is a front perspective view of a first alternative position of the mobile computer;

FIG. 7 is a rear perspective view of the first alternative position of the mobile computer of FIG. 6;

FIG. 8 is a top elevational view of the first alternative position of the mobile computer of FIG. 6;

FIG. 9 is a right side view of the first alternative position of the mobile computer of FIG. 6;

FIG. 10 is a front perspective view of a second alternative position of the mobile computer;

FIG. 11 is a rear perspective view of the second alternative position of the mobile computer of FIG. 10;

FIG. 12 is a top elevational view of the second alternative position of the mobile computer of FIG. 10;

FIG. 13 is a right side view of the second alternative position of the mobile computer of FIG. 10;

FIG. 14 is a front perspective view of a third alternative position of the mobile computer;

FIG. 15 is a rear perspective view of the third alternative position of the mobile computer of FIG. 14;

FIG. 16 is a front view of the third alternative position of the mobile computer of FIG. 14;

FIG. 17 is a right side view of the third alternative position of the mobile computer of FIG. 14;

FIG. 18 is a rear view of the third alternative position of the mobile computer of FIG. 14; and,

FIG. 19 is a top plan view of the third alternative position of the mobile computer of FIG. 14.

The broken lines, as shown in FIGS. 1 through 19, are for illustrative purposes only and form no part of the claimed design.
